GRINDING MACHINE

Harold L. Blood, Worcester, Mass., assignor to
 The Heald Machine Company, Worcester,
 Mass., a corporation of Massachusetts

Application June 11, 1931. Serial No. 543,648

15 Claims. (Cl. 51—50)

The invention relates to grinding machines and particularly to internal grinding machines which are used for grinding the internal cylindrical or conical surfaces of sleeves, gears, bushings and like articles.

In grinding with a machine of the type disclosed in Patent No. 1,682,672 issued August 28, 1928 to Guild or of the type disclosed in Patent No. 1,731,719 issued October 15, 1929 to Kempton and Gallimore, the grinding wheel enters the work and is reciprocated therein to produce a relative traversing movement between the wheel and the work until the workpiece is ground to the desired finished size when the wheel is automatically removed from contact with the workpiece and is run out automatically to its rest position. In such machines, the wheel is fed transversely against the surface being ground, in order that the wheel will cut progressively deeper and deeper into the workpiece, by a relative cross-feed movement of said grinding wheel and work, which movement is imparted in a step-by-step relation by automatic mechanism responsive to the relative traversing movement, said cross-feed mechanism being actuated during the entire operation of the machine. The progressive cross-feed which urges the wheel against the surface being ground carries the wheel with greater and greater pressure against the workpiece, the surface of the workpiece being removed to a less depth than the corresponding movement of the wheelhead toward the workpiece. This pressure causes the spindle carrying the wheel to be sprung somewhat and this spindle spring together with the excessive pressure built up between the wheel and work produces an uneven grinding action with the result that the finished surface is rough and often irregular. During the normal reciprocatory movement of the wheel over the surface being ground the pressure established by the cross-feed movement is distributed over the entire width of the grinding wheel. However, when the wheel is being separated from the work at the completion of the grinding, the pressure area is diminished, and the pressure for each unit of area is thereby increased as the wheel is being withdrawn beyond the end of the bore of the workpiece, with the resultant "bell-mouthing" in the bore of said workpiece, producing a ground surface which is not uniform throughout.

The patent to Kempton and Gallimore, above cited, provides for a reduced cross-feed movement during the final grinding operation, which provides a more even finished surface, although

the objectionable bell-mouthing still occurs when the wheel is separated from the work.

Ideal grinding conditions prevail when there is practically no pressure exerted by the wheel against the work, and the object of the present invention is to provide a grinding machine which will relieve the pressure built up by the cross-feed movement of the grinding wheel prior to withdrawal of the wheel from the work and which incorporates the advantages of the grinding machines disclosed in the above cited patents. According to the present invention, the cross-feed movement of the grinding wheel is discontinued before the wheel is withdrawn from the work so that the wheel in completing the grinding is allowed to traverse the surface being ground with no cross-feed movement being imparted thereto, the small amount of pressure or spindle spring which was built up during the operation of the cross-feed movement causing the wheel to grind under gradually diminished pressure until the spring in the spindle is no longer effective or, in other words, until the grinding wheel sparks out, after which the wheel and work are separated.

This invention is similar to the invention disclosed in the copending application of Heald, Serial No. 542,240, filed June 5, 1931, in which the mechanism by which the cross-feed is discontinued prior to withdrawal of the grinding wheel from the workpiece and is mechanically actuated. The present invention provides electrically controlled mechanism by which to procure cessation of the cross-feed prior to withdrawal of the wheel from the workpiece. Other and further objects and advantages of the invention will appear from the following detailed description thereof, reference being had in this connection to the accompanying drawings, wherein—

Fig. 1 is a front elevation of an internal grinding machine embodying the invention.

Fig. 2 is an enlarged front elevation of the cross-feed mechanism parts being broken away to show the construction thereof.

Fig. 3 is a wiring diagram.

Fig. 4 is an alternative wiring diagram for use with a modified grinding machine.

Like reference characters refer to like parts throughout the drawings.

Referring first to Fig. 1, an internal grinding machine is shown having the reciprocating table or carriage 1 ordinarily provided in internal grinding machines. In such a machine, either the grinding wheel or the work to be ground may be carried on the table 1, the recip-

100

105

110

location of the latter being utilized in either case to produce a relative traversing movement between the grinding wheel and the work. As here shown, the table 1 supports and carries a wheelhead 2, while the work which is to be operated upon is held in a workhead 3, the latter being carried by a bridge 4 which spans the slideways provided by the machine frame for the back and forth movement of the table 1.

10 The grinding wheel 5 is carried on a spindle 6 which is suitably journalled in the wheelhead 2, and any suitable means, which need not herein be described, is provided to rotate said spindle 6 and wheel 5. The workpiece, which is held 15 within a suitable chuck on the inner end of the workhead 3, is also rotated, but desirably at a slower speed.

10 The reciprocation of the table 1 to cause the rotating grinding wheel 5 to make the required 20 interior traverse of the rotating workpiece may be imparted in any well-known manner, as for instance by the use of the fluid pressure controlling and reversing mechanism described in United States Letters Patent No. 1,582,468, 25 granted April 27, 1926 to Heald and Guild. Such mechanism is now well-known in grinding machines and requires no detailed description; it is sufficient to note for present purposes, that the driving means employed for the reciprocation 30 of the table 1, be it hydraulic drive, or gear drive, or any other type, procures the reversal of said table at each end of the latter's normal working stroke by the use of spaced adjustable dogs 7 and 8, carried by the table 1 and adapted 35 alternately to engage and to move a reversing member 9; the latter, during the grinding operation, when the wheel 5 is moving back and forth within the workpiece 6, is situated between the two dogs 7 and 8 in a position to be struck alternately by said dogs, and by its consequent 40 movement, first in one way and then the other, effects the reversals in the travel of the table 1.

40 The above described mechanism is all old and well known in the art and of itself forms no part 45 of the present invention. The latter involves the attainment, in connection with such or similar grinding machine instrumentalities, of the novel and useful objects and results hereinbefore set forth. In the present machine, a cross-feed 50 between work and grinding wheel is obtained by moving the wheelhead 2 transversely of the reciprocating table 1 but, obviously, the invention is not limited in this respect, since the cross-feed mechanism, as hereinafter described, might as readily be applied to the transverse movement of the workhead 3.

55 The wheel head 2 of the machine is mounted on a cross-slide, not shown, which is adapted to have an in and out movement on the reciprocating table 1; movement of the slide is obtained by rotation of a threaded shaft 11 held against longitudinal movement in the table 1, the shaft engaging an internally threaded member secured to the cross-slide. Rotation of the threaded shaft 60 11 to procure the in and out movement of the cross-slide is effected in the following manner:—

65 As the table 1 is reciprocated over the work, a cam 12 which is adjustably mounted on a horizontal extension 13 of the workhead 3 engages 70 a roller 14, Fig. 2, mounted on an arm 15 which is journalled on a stud 16 on the table 1, thereby rocking said arm upwardly. A pawl 17 which is pivotally mounted on the outer end of the arm 15 engages at each rocking movement of the arm 75 with one of the teeth on a ratchet wheel 18, im-

parting a step-by-step rotary movement thereto. The ratchet wheel 18 (Fig. 2) is operatively secured to the threaded shaft 11 in any desired manner, for example, in the manner shown in the above cited patent to Guild, and the step-by-step 80 rotation of the table 1 imparts, through the operative connection, a step-by-step cross-feed movement to the cross-slide. A hand wheel 19 is rigidly secured to the ratchet wheel 18, and provides a means by which the cross-slide may be repositioned after the completion of a grinding operation to place the grinding wheel in a position to enter a new workpiece.

85 After a predetermined period of grinding the grinding wheel is withdrawn from operative relation to the workpiece to permit a dressing operation to be performed on the wheel to provide a smooth grinding surface and, after being again placed in operative relation to the work, is withdrawn after the workpiece is completely ground. 90 The separation of the wheel and the work is obtained by gauge devices of the type disclosed in Patent No. 1,534,302, issued April 21, 1925 to Conradson et al. The particular gauge construction is not, of itself, the invention in this application. It is sufficient, for the purposes of the present invention, to note that a roughing gauge and a finish gauge are mounted in the workhead and are pressed against the end of the workpiece at each reciprocation of the table. When the 95 workpiece reaches a predetermined size prior to the final grinding operation, the roughing gauge enters the internal surface of the workpiece. The longitudinal movement imparted to the gauge as it enters the workpiece, makes an electrical contact 100 thereby closing an electrical circuit, which circuit is used, in the present application, to procure separation of the wheel and work for the dressing or truing operation on the wheel. The separation of wheel and work is accomplished in 105 110 the following manner:—

110 Referring to the wiring diagram of Fig. 3, the contact points 20 and 21 represent the gauge contacts which are connected when the rough gauge 115 enters the bore of the workpiece to cause the table 120 to be withdrawn from normal reciprocatory position for the dressing operation on the wheel. The contact 20 is connected to a ground 22 by a lead 23, and contact 21 is connected by a lead 24 to one side of an electromagnet 25, the other terminal 125 of the electromagnet being connected by a lead 26 to one plate 27 of a switch 28, the latter being mounted on the front of the machine. A moving blade 30 of the switch is in contact with the plate 27, said blade 30 being connected by a lead 31 to 130 one terminal of a generator 32, the other terminal of the latter being grounded at 33. A manually operated switch 34 is provided in the ground connection to render the electrical circuits inoperative, said switch being normally closed. Accordingly, when the circuit is closed by engagement of the contacts 20 and 21, switch 34 being in closed position, the electromagnet 25 is energized 135 causing attraction of an armature member 35 and the consequent elevation of its attached lever arm 140 36, these parts being pivoted at 37 on the front of the machine. Such movement of the lever arm 36, responsive to the engagement of gauge contacts 20 and 21 is made use of automatically to interrupt the grinding operation on the workpiece 6 for the dressing and truing of the grinding wheel 5, in advance of the final and finishing cuts taken by said wheel to bring the workpiece to the desired size. This involves the withdrawal 145 of the grinding wheel 5 from the workpiece, and 150

the disposal in the temporarily amplified path of movement of said wheel of a dressing device or diamond 38; these two operations are effected through the medium of the lever arm 36 in the manner fully described in the patent issued to Heald and Guild, No. 1,779,094, granted October 21, 1930, in which the dressing device 38 is moved into operative position through the medium of fluid under pressure. It is sufficient to note, for purposes of this application, that, as described in said Heald and Guild Patent No. 1,779,094, the dresser point 38 is lowered into operative position by the downward swinging movement of a carrying member 40. When the lever arm 36 is moved, a downward extension 41 thereof communicates said movement to a valve, not shown, thus making the pressure fluid active, through suitable connections, against a piston, not shown, which is operatively associated with the member 40 thereby to swing the dresser point 38 from the inoperative position that it normally occupies down into its operative position in the path of grinding wheel 5. The invention, of course, is not limited to the above described use of pressure fluid for disposing the dresser 38 in operative position; obviously, any other type of dresser moving mechanism may be used.

As before stated, the other operation inaugurated by said engagement is the automatic amplification of the reciprocatory path of table 1 to carry the wheel 5 past the dresser 38. As shown in Fig. 1, the left hand table dog 8 which limits the right hand movement of table 1, is carried by a block 42 which, instead of being secured directly to the table 1 as is the case with the block 43 of dog 7, is mounted so as to be capable of sliding freely longitudinally of said table. Under normal conditions, when the table is making its usual working reciprocations to traverse the grinding wheel 5 back and forth within the work-piece, the block 42 of dog 8 is held in definite spaced relation to a block 44, which latter, the same as the block 43 of right hand dog 7, is a stationary block adapted to maintain its predetermined setting or adjustment longitudinally of the table 1.

The device employed to hold the slidable block 42 in spaced relation to the fixed block 44 is here shown as a latch lever 45 pivoted on block 44 and having its free end disposed by gravity in abutting relation to a shoulder on block 42, thereby holding the block 42 at a predetermined distance to the right of block 44. When the latch member 45 is lifted to free its end from the shoulder, the normal connection between the sliding block 42 and the fixed block 44 is broken, and when this occurs on the right hand movement of table 1, the dog 8 will bear without effect against the member 9. Thus the right hand movement of the table 1 on this particular stroke will be extended beyond the usual reciprocatory working path and the grinding wheel 5 will be carried out of the hole in the workpiece to a point just beyond that occupied by the dressing device, which latter, as already described, has been moved into operative position as the amplified right hand travel of table 1 begins. This amplified right hand travel of table 1 involves relative sliding movement between said table and the block 42, owing to the obstruction which the reversing member 9 imposes against the dog 8 to prevent the block 42 from moving with the table; finally the block 42 brings up against the block 44, whereupon the solid backing thus afforded for the block 42 enables the dog 8 to shift the member 9. This

procures reversal of the table 1 and the left hand movement of said table thus inaugurated is caused to restore the parts automatically to normal position in the manner disclosed in the above identified patent to Guild, so that the dog 8 is again in the operative position of Fig. 1.

Said single amplified reciprocation of the table 1 for wheel dressing purposes is, in the present invention, inaugurated automatically upon a predetermined preliminary amount of grinding having been done on each workpiece, by the making of electrical contacts through the terminals 20 and 21 as already described, thus moving the lever 36 about its pivot 37. The upper portion of the lever 36, upon movement of this lever during normal working traverse of the grinding wheel 5, engages and lifts the latch lever 45, thus causing the above described amplified movement of the table 1, which carries the grinding wheel 5 to the right past the diamond 38 and then to the left, again passing said diamond before resuming the normal reciprocatory traverse of the workpiece 6. Thereupon, by any suitable means, such as that shown and described in the aforesaid Patent No. 1,779,094 of Heald and Guild, the diamond 38 is rocked upwardly into the inoperative position that it normally occupies.

On this amplified right hand dressing stroke of the table 1, an arm 46, Fig. 3, pivoted at 47 on the block 44, and hanging by gravity in the position shown in Fig. 3, strikes an arm 48, Fig. 3, of movable switch member, thereby rocking said switch member away from bar 27 to prevent a repetition of the dressing stroke.

The cross-feed movement is discontinued at this point in the grinding operation to permit the pressure of the grinding wheel during the subsequent grinding gradually to diminish until the grinding wheel sparks out as above pointed out. Cessation of the cross-feed movement is obtained during the amplified right hand dressing stroke of the table 1, on which dressing stroke, as above pointed out, the switch member 30 is rocked away from the bar 27, thereby moving said member 30 into engagement with a plate 50 which is arranged to procure disengagement of the pawl 17 from the ratchet wheel 18 in the following manner:—

Referring to the wiring diagram of Fig. 3, the plate 50 is connected by a lead 51 to one terminal of an electromagnet 52, the other terminal being connected to a ground 53 by lead 54. Since the moving blade 30 of the switch is connected to one terminal of the generator 32, engagement of the blade 30 and plate 50 energizes the electromagnet 52 causing attraction of an armature member 55. This movement of the armature disengages the ratchet and pawl as follows:—

Referring now to Fig. 2, a depending arm 56 is pivoted on a stud 57 on the table 1 and carries adjacent the lower portion thereof a cam 58 which is adapted upon swinging movement of the arm 56 to engage with a depending lug 60 on the pawl 17 to withdraw said pawl from engagement with the ratchet 18. The lower end of the arm 56 is connected to one end of the armature 55 by a rod 61, the opposite end of the armature being pivoted at 62 to a portion of the table 1. Attraction of the armature 55 by the electromagnet 52 moves the cam 58 into engagement with the lug 60, thereby maintaining the pawl 17 out of engagement with the ratchet wheel 18 until the electromagnet is deenergized; said magnet is deenergized at the beginning of a subsequent grinding operation as will be hereinafter pointed out.

After the wheel dressing operation above described, grinding is resumed upon the workpiece 6 and continued, without cross-feed movement, until a finish gauge of the type disclosed in the 5 above mentioned Conradson et al. patent, and actuated in a similar manner, enters the work. The particular operation of this gauge is not of itself the invention in this application, and it is sufficient to note, as pointed out with reference 10 to the roughing gauge, that when the workpiece reaches the exact desired size, this size being the size of a completed workpiece, a finish gauge enters the internal surface of the work, the longitudinal movement of the gauge as it enters the 15 work making an electrical contact, thereby closing a circuit which acts in the present application to withdraw the wheel from the work and to cause the wheel to be carried to rest position. In the diagram of Fig. 3, the contact points 63 20 and 64 represent the contacts between which electrical connection is made when the finish gauge enters the workpiece. Since the contact 63 is grounded at 65 and the contact 64 is connected by a lead 66 to one terminal of an electromagnet 25 67, the other terminal being connected by a lead 68 to the lead 31 from the generator 32, engagement of the contacts 63 and 64 energizes the magnet 67, thereby causing attraction of the armature 70 pivoted on the same spindle 37 which 30 forms the pivot for the armature member 35. The armature member 70 provides a lever arm 71 for cooperation with the left hand table dog 8 in the following manner:—

Said table dog 8, as shown in Fig. 1, is pivoted 35 to its carrying block 42, and normally rests by gravity against a pin, thereby to maintain its free end in position to engage and move the reversing member 9 at the end of the right hand normal working stroke of the table 1. When the magnet 67, in response to the grinding of the workpiece 40 to the exact desired size, is energized, the lever arm 71 is raised into the path of dog 8, and the latter on the right hand movement of table 1, by reason of its pivotal mounting is free to ride on 45 the upper surface of said lever arm; thus the striking end of said dog 8 is carried clear of the reversing member 9, and the table 1 continues its movement to the right, carrying the grinding wheel 5 out of the workpiece and well past the 50 then inoperative dressing device 38, said table ultimately carrying the grinding wheel 5 into the position illustrated in Fig. 1, and there being brought to a full stop by any suitable means, such for example, as shown in the above cited Heald 55 and Guild Patent No. 1,582,468. Thus with the coming to size of a given workpiece 6, the mechanism automatically secures the complete cessation 60 of the grinding operation, and the full longitudinal separation of the grinding wheel from the workpiece, permitting access to said workpiece in said machine of a new unground workpiece while the grinding wheel 5 is entirely out of the way.

On the return to working position, from the full 65 withdrawal position shown in Fig. 1, an arm 72, pivoted at 47 and hanging by gravity in the position shown in Fig. 3, strikes an arm 73 of the movable switch member, thereby rocking said 70 switch member so that its connector 30 is returned to the position shown in Fig. 3, in readiness for the energization, at the proper time in the grinding of the next workpiece, of the electromagnet 25 which inaugurates, as above described, the wheel dressing operation. As shown in Fig. 3,

arms 48 and 73 of movable switch member 30 are offset from one another, as are also the corresponding striking arms 46 and 72 respectively of the table 1. During the withdrawal for the dressing operation, the arm 72 is not carried far enough to engage the arm 73 so that the movable member is not reversed until the wheel is moved into position for grinding a new workpiece.

From a consideration of Fig. 3, it will be seen that as the movable switch member is returned to engagement with the plate 27, on return of the table to operative position relative to a new workpiece, the circuit through the electromagnet 52 is broken by separation of plate 30 and plate 50, and the pawl 17 is thereby permitted to return to operative engagement with the ratchet 18 so that, during a subsequent grinding operation, the cross-feed movement may again be obtained in the manner above set forth until the subsequent dressing operation.

Referring to the modification shown in the diagram of Fig. 4, the connection of the operating parts is intended for use in a machine of the type shown in the above cited Guild patent, in which construction the movements of the reciprocating 100 table are procured by movements of the mechanism which obtains the cross-feed. For the purposes of the present invention, it is sufficient to note that the grinding wheel is withdrawn from the workpiece for a dressing operation before the 105 grinding is completed and is again withdrawn, after the final cut, to rest position in order to permit insertion of an unground workpiece, by mechanism mounted on and cooperating with the cross-feed mechanism, the operation of which 110 will be described with relation to the machine instrumentalities of Fig. 1. The present modification contemplates the cessation of the cross-feed movement a predetermined time prior to the separation of the wheel and work as will be pointed 115 out. An annular cam and ratchet ring 80 is disposed about and rotates with the hub of a hand wheel of the cross-feed mechanism corresponding to the hand wheel 19, above mentioned, and is actuated in a similar manner by a pawl and ratchet 120 mechanism, the pawl being indicated in this figure at 81. The cam ring 80 carries a cam projection 82 which, in the clockwise rotation of the hand wheel and ratchet during the cross-feed movement of the grinding wheel, engages successively with two adjustable screws 83 and 84, engagement with screw 83 causing withdrawal of the wheel for the dressing operation and engagement with the screw 84 causing withdrawal of the wheel to rest position after the final grinding 130 operation. The screw 83 is carried by a pivotal member 85 and the rocking of that member, under the influence of the cam projection 82 causes engagement of two electrical contacts 86 and 87. Similar movement of the screw 84 which is carried 135 by a pivotal member 88, causes the engagement of electrical contacts 90 and 91; engagement of the first contacts 86 and 87 closes a circuit which causes the wheel dressing instrumentalities of the machine to be brought into operation, while engagement of the contacts 90 and 91 causes longitudinal separation of the grinding wheel 5 from the workpiece 6, the former being moved to its extreme right hand position.

When the terminals or contacts 86 and 87 make 145 contact, an electrical circuit is formed which causes the table 1 to have an amplified stroke to the right, in order to withdraw the grinding wheel 5 from the work, and simultaneously causes a wheel dressing member or diamond 38 to move 150

into the amplified path of said grinding wheel, thereby to true the periphery of the latter as it passes the point of said diamond. As shown by the wiring diagram, electrical current may be supplied by a direct current generator 92 driven continuously by any suitable means, not shown, from the same source of power that is used for the rotation of the grinding wheel or the work spindle. One terminal of this generator 92 is connected to a ground 93 by a lead 94, the latter carrying a switch 95, normally in closed position, by which the electrical control through the machine may be disconnected; the other terminal of the generator is connected to a supply lead 96, the latter being connected by a lead 97 to an oscillatory plate 98 of a switch which is mounted on the front of the machine. In the normal position of the oscillatory plate 98, it is in contact with a plate 100 which is connected by a lead 101 to one terminal of an electromagnet 102; the other terminal of said electromagnet is connected by a lead 103 to the terminal 87. The terminal 86 is connected by a lead 104 to a ground 105. When the cam 82 engages and lifts the screw 83, the terminals 86 and 87 are brought together closing the circuit through the electromagnet 102 and energizing the magnet, thereby causing attraction of an armature member 106 and the consequent elevation of its attached lever arm 107, these parts being pivoted at 108 on the front of the frame. Such movement of the lever arm 107, responsive to the engagement of cam 82 and screw 83, operates in the manner of the above described lever arm 36 automatically to interrupt the grinding operation on the workpiece for the dressing and truing of the grinding wheel in advance of the final and finishing cuts taken by said wheel to bring the workpiece to the desired size; a downward extension 110 of the lever arm 107 serving to actuate the dressing device in the manner of the downward extension 41 above mentioned.

On the amplified right hand dressing stroke above pointed out the oscillatory plate is rocked out of engagement with the plate 100, thereby breaking the circuit through the electromagnet 102 and preventing a repetition of the dressing stroke, the oscillatory plate being actuated by an arm 111, pivotally mounted at 112 on a portion of the reciprocating table, in the manner of arm 46, said arm 111 engaging an arm 113 on plate 98 in line therewith.

Following this single extended movement of the table, the wheel is again returned to the work in the manner disclosed in the above identified 55 Guild patent for completion of the grinding operation. This continued grinding operation involves a further rotation of the cam 82 in a clockwise direction eventually bringing the cam into engagement with and lifting the screw 84, thereby causing the terminals 90 and 91 to be brought together, contact of these terminals causing the table and the grinding wheel mounted thereon to be withdrawn from engagement with the work a predetermined time subsequent 60 to the engagement of contacts 90 and 91 in the following manner:—The terminal 90 is connected by a lead 114 to the ground 105 and the terminal 91 is connected by a lead 115 to a solenoid coil 116, the opposite end of said coil being connected by a lead 117 to the supply lead 96 from the generator. Upon the energization of the solenoid 116 by contact of terminals 90 and 91, a switch member 118 is attracted by the solenoid and provides an electrical connection between terminals 70 120 and 121. Terminal 120 is grounded at 122

and terminal 121 is connected by a lead 123 to one terminal of a time relay motor 124, the other terminal of said motor 124 being connected through a lead 125 and the arm 126 of a switch 127 to a switch terminal 128, the latter terminal being connected by a supply lead 130 to the lead 96. The other arm 131 of the switch 127 is connected by a lead 132 to one terminal of an electromagnet 133, the other terminal of said magnet being connected to the supply lead 96. When the switch 118 closes the circuit between terminals 120 and 121, the time relay motor 124 is put in operation so that a predetermined time after engagement of contacts 90 and 91, the switch 127 is actuated, breaking the connection between arm 126 and terminal 128 and closing a circuit through the arm 131 to the electromagnet 133, a terminal 134 for the switch arm 131 being grounded at 135 to complete this circuit. Energization of the electromagnet 133 causes attraction of the armature member 136 and the consequent elevation of its attached lever arm 137, these parts being pivoted on the shaft 108 which also forms the pivotal support for the lever 107. Upward movement of the arm 137 acts in the manner of the 100 arm 71 to separate the wheel and the workpiece just as the workpiece reaches the exact desired size.

When the cam 82 engages and actuates the screw 84, the cross-feed movement is discontinued 105 to permit grinding to continue under gradually diminished pressure until the wheel is withdrawn by operation of the time relay motor. An arcuate shield 138 is mounted over the ratchet wheel in spaced relation to the cam 82 and is adapted to 110 engage beneath the pawl 81 to separate said pawl from the ratchet actuated thereby as soon as the screw 84 has been moved by the cam 82 whereby the time relay mechanism is put in operation. The shield 138 allows the pawl to continue the 115 reciprocations imparted thereto by the reciprocating table movements without transmitting any movement to the hand wheel or the cross-feed mechanism actuated thereby.

It will thus be apparent that the cross-feed 120 movement of the grinding wheel is discontinued at approximately the same time that the screw 84 is actuated and, since the actuation of the screw 84 closes the circuit by which the wheel is separated from the work, that the separation 128 will occur at a predetermined time following the closing of the said circuit depending upon the time interval as adjustably established by the setting of time relay motor.

The separation of wheel and workpiece by the 130 lever 137 causes the table 1 to be carried to its extreme right hand position to permit insertion of an unground workpiece into the workholding chuck. Upon subsequent return of the wheel to operating position for grinding the new workpiece, said return being effected by movement of the table 1, an arm 139, pivotally mounted on the support 112 for arm 111, engages an arm 140 on the plate 98, and rocks said plate into normal position in engagement with plate 100 to permit 140 during the succeeding grinding operation, the energization of magnet 102 for withdrawal of the table for a dressing operation on the wheel, as above pointed out.

The construction of the embodiment shown in 145 Fig. 3 is not limited to the construction shown since, from a consideration of Fig. 4, it will be readily apparent that a time relay motor or other time control device may be readily inserted in the circuit which controls the electromagnet for 150

separating the pawl and ratchet, with the result that the cross-feed for the grinding wheel may be discontinued in any predetermined time relation to the movement either of the rough gauge which actuates the contacts 20 and 21 or the finish gauge which actuates the terminals 63 and 64.

I claim,

1. In a grinding machine, a grinding wheel having an operative position in engagement with a workpiece, and an inoperative position axially spaced from the workpiece, means to procure a cross-feed movement between said wheel and a workpiece, means to procure axial withdrawal of said wheel to inoperative position, and electrically actuated means to procure cessation of said cross-feed movement prior to said withdrawal.
2. In a grinding machine, a grinding wheel, a cross-feed mechanism to procure a cross-feed movement between said wheel and a workpiece, means actuated by said cross-feed mechanism to procure a withdrawal movement between said wheel and workpiece, and means to procure cessation of said cross-feed mechanism prior to said withdrawal movement, said means to procure the withdrawal movement including a circuit actuated by a time relay motor.
3. In a grinding machine, a grinding wheel, means to procure a cross-feed movement relative to a workpiece, means to procure an extended movement of said wheel relative to the workpiece prior to completion of the grinding operation and subsequent return of the wheel and workpiece to operative position, and means responsive to said extended movement to procure cessation of said cross-feed movement when the wheel again engages the workpiece.
4. In a grinding machine, a grinding wheel, means to procure a cross-feed movement of said wheel relative to a workpiece, a gauge adapted to have an extended movement when the workpiece is ground to a predetermined size prior to the completion of the grinding operation, means actuated by the extended movement of said gauge to procure cessation of said cross-feed movement, and means subsequently operative to procure withdrawal of the wheel from the workpiece.
5. In a grinding machine, a grinding wheel having an operative position in engagement with a workpiece and an inoperative position axially spaced from said workpiece, mechanism to procure a cross-feed movement between said wheel and work, means actuated by said mechanism to procure axial separation of said wheel and work to inoperative position, and means to procure cessation of the cross-feed movement at a predetermined time interval prior to said separation, said time interval being determined by a time relay mechanism.
6. In a grinding machine, a grinding wheel having a traversing movement relative to a workpiece, mechanism responsive to said traversing movement to procure a cross-feed movement between said wheel and workpiece, mechanism to procure withdrawal of said wheel from the workpiece before completion of the grinding operation, means responsive to said withdrawal movement to procure cessation of the cross-feed movement, means to return said wheel to the work, and further mechanism to procure separation of said wheel and work when the workpiece is ground to size.
7. In a grinding machine, a grinding wheel

having a traversing movement in operative relation to a workpiece, mechanism responsive to said traversing movement to procure a cross-feed movement between said wheel and workpiece including a ratchet wheel actuated by a pawl, a gauge, mechanism responsive to said gauge to procure an extended movement of said wheel relative to the workpiece to withdraw said wheel from the workpiece when the workpiece is ground to a predetermined size, magnetic means actuated by said extended movement to withdraw said pawl from said ratchet wheel, mechanism subsequently to return said wheel to operative position, and further gauge means thereafter to procure an extended movement when the workpiece is completed, said magnetic means maintaining said pawl in spaced relation to said ratchet wheel during the subsequent operations on said workpiece.

8. In a grinding machine, a grinding wheel having a traversing movement in operative relation to a workpiece, mechanism responsive to said traversing movement to procure a cross-feed movement between said wheel and workpiece including a pawl for actuating a ratchet wheel, withdrawal means responsive to said cross-feed movement to procure a withdrawal movement of the wheel from the work, other means responsive to said cross-feed movement to separate said pawl from said ratchet when said withdrawal means are actuated, said withdrawal means including a circuit having a time relay therein to procure said withdrawal movement a predetermined time subsequent to the cessation of the cross-feed movement.

9. In a grinding machine, a grinding member and a workholding member, a table on which one of said members is mounted, said table having an operative position with the grinding member in engagement with a workpiece in said workholding member, and an inoperative position with said grinding member axially spaced from the workpiece, means to procure a cross-feed movement between said grinding member and said workpiece, automatic means to procure axial separation of said grinding member and said workpiece by movement of said table to inoperative position, and electrically actuated means to procure cessation of the cross-feed movement prior to axial separation of the grinding member and the workpiece.

10. In a grinding machine, a grinding wheel, means to procure a cross-feed movement of the wheel relative to a workpiece, a gauge adapted to engage the ground surface of the workpiece when the latter is ground to a predetermined size to procure separation of the wheel and workpiece, said wheel and workpiece being subsequently automatically returned to operative position, and means actuated by said separation to procure cessation of said cross-feed movement.

11. In a grinding machine, a grinding wheel and a workpiece, a table on which one of said members is mounted, means to procure a cross-feed movement between said wheel and workpiece, means to procure movement of the table for a separation between said wheel and workpiece before completion of the grinding operation, means responsive to said separation to procure cessation of the cross-feed movement, means to return said wheel and work to operative relation, and further mechanism to procure separation of said wheel and work when the latter is ground to size.

12. In a grinding machine, a grinding wheel, a

- mechanism to procure a cross-feed movement between said wheel and a workpiece, mechanism to procure withdrawal of said wheel from the workpiece before completion of the grinding operation, means responsive to said withdrawal to procure cessation of the cross-feed movement, means to return said wheel to the work and further mechanism to procure separation of said wheel and work when the latter is ground to size. 5 80
- 10 13. In a grinding machine, a grinding wheel, a cross-feed mechanism for procuring a cross-feed movement between said wheel and a workpiece, a time relay motor, means for procuring cessation of the cross-feed movement and for setting said time relay motor in operation, and means controlled by said motor for procuring an axial withdrawal movement between said wheel and the workpiece a predetermined time after cessation of the cross-feed movement. 15 85
- 15 14. In a grinding machine, a grinding member and a workholding member, a table on which one of said members is mounted, said table having an operative position with the grinding member in engagement with a workpiece in said workholding member and an inoperative position with said grinding member axially spaced from the workpiece, means to procure a cross-feed movement 90
